UNITED STATES PATENT OFFICE.

ZACHARY T. HOSKINS, OF BROOKHAVEN, MISSISSIPPI.

CORSET.

No. 880,532.

Specification of Letters Patent.

Patented March 3, 1908.

Application filed July 18, 1907. Serial No. 384,412.

To all whom it may concern:

Be it known that I, ZACHARY T. HOSKINS, citizen of the United States, residing at Brookhaven, in the county of Lincoln and 5 State of Mississippi, have invented certain new and useful Improvements in Corsets, of which the following is a specification.

My invention relates to an improved closure for corsets, corset waists and the like, 10 and it has for its object the production of a device of this nature which is adapted to be applied to a corset, corset waist, or similar garment of the ordinary form or construction.

The primary object of my invention is the 15 provision of a closure adapted for insertion between the adjacent edges of a corset or corset waist and which, while closing the space between such adjacent edges and adapted to be laced or otherwise flexibly attached thereto, will provide the maximum of elasticity 20 and freedom of movement to the wearer.

A further object of my invention is the provision of a closure which will permit of the 25 separation of the adjacent edges of the garment to which it is applied, but which at the same time will completely close the aperture between such edges when the same are separated within reasonable limits.

Other objects of the invention will be set 30 forth in the following detailed description and in connection with said description attention is directed to the accompanying drawings illustrating the closure in its preferred form of embodiment, it being understood 35 that various changes and modifications may be made therein without exceeding the scope of the concluding claims.

In the drawings Figure 1 is a rear elevation of a corset provided with my invention; Fig. 40 2 is a perspective view of the closure and Fig. 3 is a transverse section thereof on the line 3, 3 of Fig. 2.

1 designates a base or bottom strip preferably formed of a double thickness of an 45 elastic fabric, and having at its sides strengthening stays 2, 2, these stays operating to hold the base portion smoothly in position, and to cause such portion to conform to the body of the wearer. 3 represents an upper strip, also 50 preferably formed of double thickness of material, and secured at its central portion to the bottom strip 1 by lines of stitching 4, 4. As an additional means of securing the parts

1 and 3 together, the meeting ends of said 55 parts are provided with binding tapes 5, 5, which are suitably stitched in place. The

strip 3 is provided at its edges with suitable stays 6, 6 which, preferably, are held between the two thicknesses of the material composing said strip. Between the stays 6 and the 60 lines of stitching 4, and on each side of said strip I provide a series of eyelets 7, 7, which receive the lacing cords 8.

9 designates a corset of any desired construction and 10, 10 the eyelets for the lacing 65 cords 8 at the adjacent edges thereof. The closure is inserted between the adjacent edges of the back of the corset in the form shown, and lacings 8 are threaded through the eyelets 10 in the edge of the corset and 70 the eyelets 7 of the closure. Preferably, these lacings are elastic cords, so that the garment can yield to the movements of the wearer. The outer portions of the strip underlie the adjacent edges of the garment to 75 which it is applied, so that under ordinary conditions the opening between the adjacent edges of the garment will be closed. Furthermore, the edges of the base portion tend to guide the adjacent edges of the corset in 80 their movement to and from each other, and the inner edges of the closure, or those of the portion 3, act as stops to prevent undue lacing of such garment as the adjacent edges thereof are caused to meet the edges of the stays 85 in such portion 3, in the action of lacing the parts.

Having thus described my invention, what I claim as new and desire to secure by Letters Patent is

1. As a new article of manufacture a closure for corsets or the like, comprising a base portion, an upper portion arranged in superimposed relation thereto, means securing said parts together approximately at their center, whereby the edges of said upper portion are left free, and means carried by the edges of said upper portion, whereby the closure may be secured between the adjacent edges of the garment.

2. As a new article of manufacture, a closure for corsets or the like, comprising a base portion, an upper portion of less width than the base portion arranged in superimposed relation thereto, means securing said parts together approximately at their center, whereby the edges of said upper portion are left free and eyelets adjacent to the edges of said upper portion.

3. As a new article of manufacture, a closure for corsets or the like, comprising a base portion, an upper portion of less width than

the base portion, and arranged in superimposed relation thereto, and eyelets adjacent to the edges of said upper portion, said base portion being provided with stays.

5 4. As a new article of manufacture, a closure for corsets or the like, comprising a base portion, an upper portion of less width than the base portion and arranged in superimposed relation thereto, eyelets adjacent to the edges of said upper portion and stays at the edges of the base portion and the upper portion.

10 5. The combination with a corset or the like having its adjacent edges provided with

eyelets, of a closure therefor consisting of a 15 base portion, a superimposed portion narrower than such base portion provided at its adjacent edges with stays and rows of eyelets adjacent thereto, whereby the edges of the garment will be adapted to aline against 20 the edges of said narrow portion in the act of lacing the closure in place.

In testimony whereof I affix my signature in presence of two witnesses.

ZACHARY T. HOSKINS.
